CLAIM

The ornamental design for a connector, as shown and described.

DESCRIPTION

FIG. 1 is a first perspective view of a connector, showing our new design;

FIG. 2 is a top plan view thereof;

FIG. 3 is second perspective view thereof;

FIG. 4 is a left elevation view thereof;

FIG. 5 is a rear elevation view thereof;

FIG. 6 is a right elevation view thereof;

FIG. 7 is a front elevation view thereof; and,

FIG. 8 is a bottom plan view thereof.

The broken lines show portions of a connector that form no part of the claim.

1 Claim, 8 Drawing Sheets
